The ornamental design for a combined tape printing machine and detachable picture frame, as shown and described.

DESCRIPTION

FIG. 1 is a front view of a combined tape printing machine and detachable picture frame;

FIG. 2 is a left-side view thereof;

FIG. 3 is a right-side view thereof;

FIG. 4 is a top view thereof;

FIG. 5 is a bottom view thereof;

FIG. 6 is a rear view thereof;

FIG. 7 is a front perspective view thereof;

FIG. 8 is a rear perspective view thereof; and,

FIG. 9 is an exploded front perspective view thereof.

The broken lines define the bounds of the claimed design, but do not form part of the claimed design.

The design is embodied in a tape printing machine have a detachable frame mounted on the front face of the tape printing machine for displaying photographs or other illustrations within the frame. The frame can be detached from the tape printing machine.
